Primary Examiner — Amanda Christensen

CLAIM

The ornamental design for a charging box for hearing aids as shown and described.

DESCRIPTION

FIG. 1 is a top, front and right side perspective view of a charging box for hearing aids showing my new design; FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and right side perspective view showing the charging box for hearing aids in an open state; and, FIG. 10 is a bottom, rear and right side perspective view showing the charging box for hearing aids in another open state.

The broken lines in the drawings illustrate portions of the charging box for hearing aids which form no part of the claimed design.

1 Claim, 10 Drawing Sheets
